UNITED STATES PATENT OFFICE.

WILLIAM S. KISINGER, OF BELLEVUE, KENTUCKY, ASSIGNOR OF TWO-THIRDS TO A. C. STIEBEL, OF ST. LOUIS, MISSOURI, AND HENRY G. STIEBEL, JR., OF CINCINNATI, OHIO.

SHEAVE.

SPECIFICATION forming part of Letters Patent No. 398,897, dated March 5, 1889.

Application filed December 6, 1888. Serial No. 292,812. (No model.)

To all whom it may concern:

Be it known that I, WILLIAM S. KISINGER, a citizen of the United States, residing at Bellevue, Campbell county, Kentucky, have 5 invented new and useful Improvements in Sheaves or Carrying-Pulleys, of which the following is a specification.

My invention relates to carrying pulleys or sheaves—such, for example, as are employed 10 in cable railways for supporting the traveling cable in the tunnel-way beneath the slot. These pulleys are subjected to very great surface-wear from the action of the cable, and at the same time are used in relatively large 15 numbers, which circumstances necessitate the cheapest practicable construction and every aid to durability. In order to meet these conditions, and also to obtain the most perfect rotundity and proper balance, I construct the 20 pulley by casting in two parts, these parts being formed to interlock together without bolts as they come from the mold, without lathe-work or other special fitting. One of these 25 parts is the permanent frame or supporting skeleton of the pulley, while the other is the replaceable section of the periphery, the two being divided upon planes transverse to the axis. The action of the interlocking devices 30 is aided by the pull of the cable, so as to hold the parts properly together. Certain minor features are also added, which will be fully described hereinafter.

Mechanism embodying my invention is illustrated in the accompanying drawings, in 35 which—

Figure 1 is a face or side view of the pulley complete, showing the permanent constituent of the pulley; Fig. 2, an edge view of the permanent constituent of the pulley detached, 40 showing the wedge form of the interlocking lugs; Figs. 3 and 4, opposite side or face views of the detachable constituent of the pulley; Fig. 5, a partial cross-section of the composite pulley, showing cross-sections of the pulley- 45 rim and the relation and "fit" of the parts at the periphery.

Referring now more particularly to the drawings, A designates the composite pulley constituting my invention, composed of a rim

in two parts, a' a^2 , of which a' designates that 50 of the supporting-frame or permanent portion, and a^2 the detachable portion or annulus. The part a' is cast with the usual hub, b, spokes c, and constitutes the supporting-frame of the pulley. Near the outer extremities of 55 the spokes are cast lugs d, with beveled outer faces, as shown in Figs. 2 and 5, and projecting outward concentrically at equal angles apart. The detachable portion or annulus a^2 is cast with corresponding recesses, e, in its inner peripheral wall, each flanked at one side by a beveled surface, e' , the parts being so formed and proportioned that when placed together the lugs d pass through the recesses e, and by a partial rotation of the annulus the 60 beveled faces of the lugs bear against and interlock with the beveled surfaces e' .

The relative position of the parts and the contour surface of the composite pulley are clearly shown in Fig. 5, wherein it will be seen 70 that the wear of the cable is wholly taken upon the removable annulus a^2 , which can be renewed at will with trifling expense. It will be also understood that the pulley is so placed in relation to the movement of the cable that 75 the pull of the latter holds the annulus to its described position against the opposing friction of the pulley in its journal-bearings. I may however provide upon each portion a 80 perforated lug, f, which register when the parts are in position, so that a pin may be driven through both to retain the parts in position; but this is not absolutely essential.

The pulley is cast with a hollow center, and may run upon a stud, or be provided with a 85 permanent axle-pivot, as desired.

The particular advantages of this construction are, first, the cheapness over pulleys separable into three or more parts; second, the economy and other advantages of dispensing 90 with bolts or separate fastening devices, and, third, by preserving the continuous circular form of parts a much more truly-circular and evenly-balanced pulley can be produced in casting than where segmental or other forms of 95 parts are used, owing to the unequal shrinkage of the metal and the displacement of patterns in the mold. A further incidental advantage is

that a much lighter pulley can be produced of a given strength, all tending not only to economy in cost of pulley, but durability and economy of maintenance in use.

5 I claim as my invention, and desire to secure by Letters Patent of the United States—

1. A composite sheave or carrying-pulley for cable railways and other uses, composed of two parts, to wit, a supporting frame or hub portion and a separable annulus containing the belt-groove or wearing portion entire, the parts being formed with corresponding interlocking lugs and recesses, whereby the same fit and are held together without bolts or other 15 separate fastenings, substantially as set forth.
2. In a composite pulley having the wearing portion of its rim detachable, a permanent or hub portion provided with concentric lugs

projecting at one side, and a detachable annulus containing the wearing portion of the 20 face and completing the rim, provided internally with corresponding recesses, by which it may be slipped over and interlocked with the lugs, substantially as set forth.

3. In a composite pulley, the combination of 25 the part a' , provided with the hub b , spoke c , and beveled lugs d , with the annulus a^2 , provided with recesses e , and beveled interlocking surfaces e' , substantially as set forth.

In testimony whereof I have hereunto set 30 my hand in the presence of two subscribing witnesses.

WILLIAM S. KISINGER.
